FISH LURE

Finn H. Magnus, Essex Fells, N. J.

Application October 21, 1955, Serial No. 38,509

Term of patent 3½ years

(Cl. D31—4)

Figure 1 is a bottom plan view of a fish lure, showing my new design;

Figure 2 is a top plan view thereof;

Figure 3 is an elevation of one side thereof viewed from approximately the plane of the line 3—3 of Figure 1, the other side being the same;

Figure 4 is a front elevation taken from 4—4 of Figure 1; and

Figure 5 is an end elevation taken from 5—5 of Figure 1.

I claim:

The ornamental design for a fish lure, as shown and described.
